UNITED STATES PATENT OFFICE.

JAMES W. BEVANS, OF HACKENSACK, NEW JERSEY.

DESIGN FOR A CHILD'S TOOTHBRUSH.

Application filed August 23, 1923. Serial No. 7,066. Term of patent 7 years.

To all whom it may concern:

Be it known that I, JAMES W. BEVANS, a citizen of the United States, residing at Hackensack, in the county of Bergen and State of New Jersey, have invented a new, original, and ornamental Design for a Child's Toothbrush, of which the following is a specification, reference being had to the accompanying drawing, forming part thereof.

The ornamental design for a child's toothbrush, as shown.

JAMES W. BEVANS.
